WINDOW

William D. Bayley, Springfield, Ohio, assignor to
The William Bayley Company, Springfield,
Ohio, a corporation of Ohio

Original application January 29, 1936, Serial No.
61,412. Divided and this application March
8, 1937, Serial No. 129,669

22 Claims. (Cl. 189—64)

This invention relates to closure assemblies for ventilating areas in windows and in more particular to ventilating areas in metallic windows.

An object of this invention is to provide a closure provided with a flexible contact engaging the frame surrounding the closure.

Another object of this invention is to provide a closure for ventilating areas of windows that is cheap, efficient, durable and dependable, that makes good contact so as to protect the interior of the building from the elements.

Another object of this invention is to provide a unitary structure for the closure and its screen that may be inserted as a unit into the ventilating area.

With the above primary and other incidental objects in view, as will more fully appear in the specification, the invention consists of the features of construction, the parts and combinations thereof, and the mode of operation or their equivalents, as hereinafter described and set forth in the claims.

Fig. 1 is a sectional view taken substantially on the line 1—1 of Figs. 2 and 4.

Fig. 2 is a sectional view taken substantially on the line 2—2 of Fig. 1.

Fig. 3 shows a vertical sectional view of another modification.

Fig. 4 is a fragmentary sectional view taken substantially on the line 4—4 of Figs. 1 and 2.

Fig. 5 is a profile view of the swinging element about the hinge shown in Fig. 2 with portions of the swinging element concealed by the basin-like sill shown by dotted lines.

This is a divisional application of my copending application Serial No. 61,412 filed Jan. 29, 1936 for Flexible window closure.

Referring to the drawings, a plurality of transversely disposed T-shaped duo-functional muntin and detention bars 20 divide the window into a plurality of spaces, some of which are glazed, as shown at 22, leaving a group of spaces 24 vacant.

The unglazed spaces 24 provide spaces for ventilation. In order to protect the occupants of the building during inclement weather, it is desirable to provide a suitable closure for the vacant spaces 24.

In the preferred embodiment, as shown in Figs. 1 and 2, the closure assembly includes a sheet metal frame located on the outside of the muntin bars. In this embodiment the frame is formed from flanged members 30 and 32 cooperating to form glazing channels 34 and weather stripping channels 36 projecting in a direction normal to the glazing. Suitable weather stripping mem-

bers 38 are seated in the channels to secure weather tightness between the closure and the fixed portion of the window whenever the closure is moved into closed position.

This closure assembly is pivotally mounted upon pintles 40 passing through suitable apertures in members 30 and 32 and through the side flanges 42 of a basin-like sill member 44. The swinging element of the hinge portion constitutes member 30, best seen in Fig. 5, with the portions thereof concealed by the flange 42 of the basin-like sill member 44 shown by dotted lines. The sill 44 has been broken, so as to only show the portion adjacent the movable closure. In this figure the movable closure has been shown independently and away from the fixed portions of the window.

As best seen by referring to Fig. 2, the basin-like sill member 44 is provided with a retaining portion 46 contoured to fit snugly over the flange 20 of the muntin bar 20 extending across the bottom of the vacant spaces 24. This portion 46 holds the basin in position by screws 47. In order to provide clearance for the muntin bar 20 extending across the vacant spaces 24 as a detention bar, the portion 46 has been notched at 48.

The flange 42 of the basin-like sill member 44 may be welded or otherwise secured to the flanges of the vertical muntin bars 20 bounding the sides of the vacant spaces 24. This gives 30 rigidity to the sill member 44, which supports the weight of the movable closure assembly.

The movable closure may be held in closed position by a latch 50 pivotally mounted at 52 to member 30 and adapted to engage a suitable catch 54. Suitable stops or links not shown may be used to limit the opening of the closure.

In addition to the movable closure, it is sometimes preferably to provide a screen extending over the vacant spaces, serving a dual purpose 40 in detention windows. It prevents the free ingress and egress of live bodies, as well as inanimate bodies such as implements, sought by inmates for effecting an escape, and it serves as a tell-tale in the event attempts are made to 45 sever the detention bars extending over the ventilating area so as to escape therethrough.

The screen disclosed in Figs. 1 and 2 includes a wire mesh screen 60 attached to substantially rectangular members 62 extending along the vertical sides and the top of the screen 60 and a substantially inverted L-shaped member 64. Members 62 contact the flanges of the muntin bars 20 bounding the ventilating area. Member 64 extends across the basin-like sill member 44 55

and forms a clearance for the bottom of the movable closure. Weep holes 68 provide drainage ducts for rain and condensation tending to accumulate in the basin-like member 44.

5. The screen is mounted in a cavity between the closure frame and the muntin bars 20 bounding the ventilating area.

Referring to the modification disclosed in Fig. 3, the closure and screen assembly have been 10 mounted so as to be partially enclosed by the stems of the muntin bars 20. In this modification the movable closure 70 includes a frame including members 72 substantially L-shaped in cross sectional area. The closure 70 is pivotally 15 attached by hinges 74, only one of which is shown, to the web of the muntin bar 20 extending across the bottom of the ventilating area. The closure is held in closed position by a suitable latch 76 in a manner similar to that described in connection with the modification 20 shown in Figs. 1 and 2.

The closure assembly 80, which has been shown as a screen, projects through the ventilating area. The screen frame 90 is formed from angle bars 25 having the flanges 92 projecting through the ventilating area and supporting the screen 94 suitably attached thereto. An abutment or snubber 96 attached to the lower flange 92 holds the screen frame at a proper height. A stop 30 97 is arranged in hooked relation with the flange of the detention bar 20 to prevent the screen frame from removal bodily inwardly. The upper flange is held in position by a diagonally arranged screw 98.

35. Although the preferred modification of the device has been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims.

Having thus described my invention, I claim:

45. 1. A closure unit for a ventilating area of a window having transversely arranged members bounding the ventilating area, said closure unit including a support and a movable glazed closure mounted in the support, said closure unit including a sheet metal frame assembly including a pair of juxtaposed members having flanges extending in directions normal to the plane of the glazing forming a channel supporting a yieldable contacting member for sealing the ventilating area when the closure unit is in closed position.

50. 2. A closure unit for a ventilating area of a window having transversely arranged members bounding the ventilating area, said closure unit including a support and a movable glazed closure mounted in the support, said closure including a sheet metal frame assembly including a pair of juxtaposed members having flanges extending in directions normal to the plane of the glazing forming a channel supporting a yieldable contacting member for sealing the ventilating area when the closure unit is in closed position and the opposite portions of said members forming a channel receiving the glazing.

65. 3. A closure unit for a ventilating area of a window having duo-functional detention and muntin bars bounding the ventilating area, said closure unit including a sheet metal member interengaging the detention bars and a movable closure attached to said sheet metal member,

said movable closure including a sheet metal frame for the glazing, said frame supporting a yieldable member arranged to seal the ventilating area when the closure is in closed position.

4. A window assembly including a frame having a plurality of transversely disposed muntin bars dividing the window into a plurality of spaces, some of which are glazed leaving a space vacant for ventilating area, a closure assembly for the ventilating area, said closure assembly including a metallic frame, a basin-like member overlapping the muntin bar bounding the ventilating area along the bottom, said closure frame being pivotally mounted in the basin member in offset relation with respect to the plane formed by the extreme surfaces of the muntin bars so as to form a cavity between the glazing and the surface of the muntin bars, and a screen for the ventilating area, said screen being positioned intermediate the closure and the adjacent outer surface of the muntin bars, the bottom of the screen frame being recessed whereby the lower edge of the closure frame is in engagement with the lower edge of the frame when the closure is in closed position.

5. In a detention window assembly a plurality of duo-functional transversely disposed muntin and detention bars dividing the window into a plurality of spaces some of which are glazed leaving a portion unglazed for ventilating area, said muntin bars presenting surfaces bounding the ventilating area substantially parallel to the plane of the glazing, a movably mounted closure frame mounted adjacent to said surfaces for contacting engagement therewith when in closed position, said closure and detention bars cooperating to form a pocket, and a screen frame mounted in said pocket, said screen frame having a reduced portion along one side thereof for accommodating the corresponding side of the closure when in closed position.

6. In a detention window assembly a plurality of duo-functional transversely disposed muntin and detention bars dividing the window into a plurality of spaces some of which are glazed leaving a portion unglazed for ventilating area, said muntin bars presenting surfaces bounding the ventilating area that lie in a plane substantially parallel to the plane of the glazing, a movably mounted closure frame adjacent said surfaces and adapted to contact same when in closed position, said closure frame and the muntin bars cooperating to form a pocket, and a screen frame having at least three sides arranged in flush relation with respect to said muntin bar surfaces, the fourth side of the screen frame having at least a portion thereof reduced in thickness, the reduced portion providing a clearance for the lower portion of the closure.

7. In a detention window assembly a plurality of duo-functional transversely disposed muntin and detention bars dividing the window into a plurality of spaces, some of which are glazed leaving a portion unglazed for ventilating area, a movably mounted closure frame adjacent the muntin bars bounding the ventilating area and adapted to contact the same, said closure frame and the muntin bars cooperating to form a pocket, and a screen frame mounted in the pocket, said screen frame having at least three sides arranged in flush relation with respect to the surfaces of the muntin bars, the fourth side of the screen frame having at least a portion thereof reduced in thickness as compared to the

other three sides, the reduced portion providing a clearance for the lower portion of the closure frame.

8. In a window assembly of the class described, a metallic frame enclosing a ventilating area, said metallic frame presenting flat surfaces substantially parallel to the outer surface of the window, a sill carried by said frame, said sill including a horizontal portion merging into an upwardly projecting flange portion, a movable closure pivotally mounted upon the sill in offset relation with respect to the main portion of the metallic frame of the window, said closure forming a cavity, a screen frame mounted in said cavity, the lower edge of the screen being seated upon said horizontal sill portion in spaced relation from said flange portion, said lower edge of the screen frame cooperating with the sill to form a channel into which the lower portion of the closure projects.

9. In a window assembly of the class described, a metallic frame enclosing a ventilating area, said metallic frame presenting flat surfaces substantially parallel to the outer surface of the window, a sill carried by said frame, said sill including a horizontal portion merging into an upwardly projecting flange portion, a movable closure pivotally mounted upon said sill, said closure having an inwardly projecting portion engaging the flat surfaces of the frame so as to form a cavity, a screen frame mounted in said cavity, the lower edge of the screen frame being seated upon said horizontal sill portion in spaced relation from said flange portion, said lower edge of the screen frame cooperating with the sill to form a channel into which the lower portion of the closure projects, the inwardly projecting portion of the closure above the screen frame clearing the same and contacting said flat surfaces when in closed position.

10. In a window assembly of the class described, a metallic frame enclosing a ventilating area, said metallic frame presenting flat surfaces substantially parallel to the outer surface of the window, a sill carried by said frame, said sill including a horizontal portion merging into an upwardly projecting flange portion, a movable closure pivotally mounted upon said sill, said closure having an inwardly projecting portion engaging the flat surfaces of the frame so as to form a cavity, the lower edge of the screen frame being reduced and seated upon said horizontal sill portion in spaced relation from said flange portion, said lower edge of the screen frame cooperating with the sill to form a channel into which the lower edge of the closure projects, the reduced portion of the screen providing a clearance for the lower portion of the closure, and weather stripping carried by the closure for engaging the sides of the frame when in closed position.

11. In a window assembly of the class described, a metallic frame enclosing a ventilating area, said metallic frame presenting flat surfaces substantially parallel to the outer surface of the window, a sill carried by said frame, said sill including a horizontal portion merging into an upwardly projecting flange portion, a movable closure pivotally mounted upon said sill, said closure having an inwardly projecting portion engaging the flat surfaces of the frame so as to form a cavity, a screen frame mounted in said cavity, the lower edge of the screen frame being reduced and seated upon said horizontal sill portion in spaced relation from said flange, the reduced portion of the lower edge providing a clearance for the

swinging movement of the closure upon the sill, the horizontal sides of the closure and the top thereof engaging the flat surfaces of the frame beyond the screen frame.

12. A window assembly including a plurality of transversely disposed muntin bars dividing the window into a plurality of spaces some of which are glazed, leaving a space vacant for ventilating area, a closure assembly for the ventilating area including a fixed metallic frame portion, a second frame movably supported upon the first frame, glazing carried by said second frame, said glazing being mounted in the frame in offset relation with respect to the planes formed by the extreme surfaces of the muntin bars so as to form a cavity between the glazing and the surface of the muntin bars, said movable closure frame having portions projecting towards the muntin bars, and a screen for the ventilating area, said screen including a screen frame positioned intermediate the glazing of the closure and the adjacent outer surface of the muntin bar, said screen frame being bounded on three sides by the inwardly projecting portion of the movable closure frame, said closure frame having an edge in engagement with the lower portion of the screen frame when the closure is in closed position.

13. A window assembly including a plurality of transversely disposed muntin bars dividing the window into a plurality of spaces, some of which are glazed leaving a space vacant for ventilating area, a closure assembly for the ventilating area including a fixed metallic frame portion, a second frame movably supported upon the first frame, glazing carried by said second frame, said glazing being mounted in the frame in offset relation with respect to the plane formed by the extreme outer surfaces of the muntin bars so as to form a cavity between the glazing and the surfaces of the muntin bars, said movable closure frame having portions projecting towards the muntin bars, and a screen for the ventilating area, said screen including a screen frame positioned intermediate the glazing of the closure and the adjacent outer surface of the muntin bar, said screen frame being bounded on three sides by the inwardly projecting portion of the movable closure frame, said screen frame having three sides of a different cross sectional contour than that of the fourth side.

14. A window assembly including a plurality of transversely disposed muntin bars dividing the window into a plurality of spaces, some of which are glazed leaving a space vacant for ventilating area, a closure assembly for the ventilating area including a fixed metallic frame portion, a second frame movably supported upon the first frame, glazing carried by said second frame, said glazing being mounted in the frame in offset relation with respect to the plane formed by the extreme surfaces of the muntin bars so as to form a cavity between the glazing and the surface of the muntin bars, said movable closure frame having channel portions projecting towards the muntin bars, weather stripping members seated in said channel portions abutting the muntin bars when the closure is in closed position, and a screen for the ventilating area, said screen including a screen frame positioned intermediate the glazing of the closure and the adjacent outer surface of the muntin bar, said screen frame being bounded on three sides by the inwardly projecting portion of the movable closure frame when said closure is in closed position.

15. A window assembly including a plurality of

transversely disposed muntin bars dividing the window into a plurality of spaces, some of which are glazed leaving a space vacant for ventilating area, a closure assembly for the ventilating area 5 including a fixed metallic frame portion, a second frame movably supported upon the first frame, glazing carried by said second frame, said glazing being mounted in the frame in offset relation with respect to the plane formed by the 10 extreme surfaces of the muntin bars so as to form a cavity between the glazing and the surface of the muntin bar, said movable closure frame having a portion arranged in parallel relation to a portion of the muntin bars, one of said portions having a portion extending normal to said portions, said portions cooperating to form a pocket, a screen for the ventilating area, said screen including a screen frame positioned in said pocket, and a resilient weather stripping member supported upon one of said frames for sealing the 15 ventilating area when the closure is in closed position.

16. A window assembly including a plurality of transversely disposed muntin bars dividing the window into a plurality of spaces, some of which are glazed leaving a space vacant for ventilating area, a closure assembly for the ventilating area including a fixed metallic frame portion, a second frame movably supported upon the first 20 frame, glazing carried by said second frame, said glazing being mounted in the frame in offset relation with respect to the plane formed by the extreme outer surfaces of the muntin bars so as to form a cavity between the glazing and the 25 surface of the muntin bars, said movable closure frame having a portion extending in parallel relation to the glazing and parallel to the portion of the muntin bars, one of said portions having a portion normal to said portions and cooperating therewith to form a pocket, the first mentioned portion supporting the glazing of the closure, a screen including a screen frame positioned in said pocket for screening the ventilating area, and a flexible member carried by one of said 30 frames adapted to abut the parallel portion of the muntin bar to seal the ventilating area when the closure is in closed position.

17. A window assembly including a plurality of transversely disposed muntin bars dividing the window into a plurality of spaces, some of which are glazed leaving a space vacant for ventilating area, a closure assembly for the ventilating area including a fixed metallic frame portion, a second frame movably supported upon the first frame for swinging movement, glazing carried by said second frame, said glazing being mounted in the frame in offset relation with respect to the plane formed by the extreme outer surfaces of the muntin bars so as to form a cavity 35 between the glazing and the surface of the muntin bars, said movable closure frame having portions projecting towards the muntin bars, and a screen for the ventilating area, said screen including a screen frame being bounded on three sides by the inwardly projecting portion of the movable closure frame, said screen frame having a portion of lesser thickness to provide a clearance between the screen frame and the closure to permit swinging movement of the closure.

18. A window assembly including a sash wherein a plurality of transversely arranged muntin bars divide a window space into a plurality of smaller spaces some of which are glazed, leaving at least one of the spaces unglazed for a venti-

lating area, characterized by a closure therefor, having a frame including a metallic structure forming channels extending along at least a portion of the margin of the closure, said channels projecting in directions at right angles to each other and interconnected by a rigid metallic portion, a body of resilient packing material seated in one of said channels, said packing material engaging the muntin bars bounding the ventilating area, and glazing seated in the other channel. 10

19. A window assembly including a plurality of transversely disposed muntin bars dividing the window into a plurality of spaces some of which are glazed leaving a space vacant for ventilating area, the muntin bars, bounding the ventilating area having surfaces projecting inwardly towards the ventilating area and parallel to said glazing, a closure assembly for the ventilating area including a fixed metallic portion, a frame movably supported upon the metallic portion for swinging movement, glazing carried by said frame, said glazing being mounted in offset relation with respect to the plane formed by said inwardly projecting surfaces of the muntin 15 bars, so as to form a cavity between the glazing and said surfaces, said movable closure frame having portions projecting toward said surfaces, and a screen for the ventilating area, said screen including a screen frame bounded on three sides 20 by the inwardly projecting portion of the movable closure frame, said screen frame having a longitudinal recess along one side thereof permitting swinging movement of the closure. 25

20. In a window having a ventilating area 30 bounded by a metallic frame having closure engaging surfaces, a closure assembly for the ventilating area, said closure assembly including a substantially rigid glass supporting frame including an L-shaped bar cooperating with a sheet 35 metal retaining member, said retaining member including a wall terminating in oppositely directed flanges, one flange cooperating with said wall and one of the legs of the L-shaped member to form a channel directed towards said closure 40 engaging surfaces, the other flange cooperating with the wall and the other leg of the L-shaped member to form a glazing seat. 45

21. A glazed closure unit for a ventilating area of a window having a plurality of transversely disposed muntin bars dividing the window into spaces some of which are glazed, leaving a group of spaces vacant as a ventilating area, said closure unit including a sheet material member interengaging the frame bounding the ventilating area, and a movable closure including a sheet material frame for the glazing, one of said frames supporting a yieldable member arranged to seal the ventilating area when the closure is in closed position. 50 55

22. A closure unit for a ventilating area of a window having transversely arranged members bounding the ventilating area, said closure unit including a support attached to one of said members and a movably mounted glazed closure 60 mounted in the support, said closure unit including a sheet material frame assembly including a pair of juxtaposed members having flanges extending in directions normal to the plane of the glazing forming a channel supporting a yieldable contacting member for sealing the ventilating area when the closure unit is in closed position. 65 70
